UNITED STATES PATENT OFFICE.

JAMES JACKSON, OF PATERSON, NEW JERSEY.

JACQUARD MACHINE.

SPECIFICATION forming part of Letters Patent No. 351,512, dated October 26, 1886.

Application filed February 20, 1886. Serial No. 192,653. (No model.)

To all whom it may concern:

Be it known that I, JAMES JACKSON, of the city of Paterson, in the county of Passaic and State of New Jersey, have invented a new and 5 useful Improvement in Jacquard Machines, of which the following is a full, clear, and exact description.

The object of my invention is to dispense with twisted cords, and to facilitate the unhooking of the harness-threads in transferring the same to another machine.

The invention consists in various parts and details and combinations of the same, as will be fully described hereinafter, and then pointed 15 out in the claims.

Reference is to be had to the accompanying drawings, forming a part of this specification, in which similar letters of reference indicate corresponding parts in all the figures.

20 Figure 1 is a sectional side elevation of part of a Jacquard machine, showing my improvement. Fig. 2 is a front elevation of the same.

Heretofore in Jacquard machines the devices which carried the harness of the loom 25 consisted of iron hooks provided on their lower ends with twisted cords, to which were attached at their lower ends the collets carrying the respective threads of the harness. The twisted cords had to be of the same length 30 throughout, in order to raise the threads of the harness equally; but it has been found very difficult to make twisted cords of the same length. With my invention I dispense entirely with the twisted cords, and at the same time I 35 attach the collets carrying the threads of the harness directly to the hooks.

Each of the hooks A consists of the vertical rod A', which is bent at its lower end to form the parallel rod A'', provided on its upper end 40 with a hook, A⁴. The rod A' is provided on its upper end with the usual bend, A³, which engages in the well-known manner with the cross-bar B, attached to the lifting-frame, which raises the hooks A, and consequently the harness of the loom, in the usual way. The parallel rods A' and A'' pass through oblong 45 apertures C' in the fixed upper grate; C, which is also provided with a ridge, C², over which fit the hooks A⁴ when the hooks A are in their lower position. The hooks A also pass through an oblong aperture, D', in the fixed grate D, which is placed above the bends A⁵ a distance 50 equal to the lift of the Jacquard machine, so

that the bends do not touch the under side of the grate D when the hooks A are in their 55 uppermost position.

To each bend A⁵ is hooked a collet, E, which is a bent and twisted spring-wire having overlapping ends, which are slightly spread apart in order to hook them over the hook A. Each 60 thread F of the harness is provided with the usual loop on its upper end, which is passed in between the overlapping ends of a collet, E, and hooked to the lower bend of the same.

It will be seen that the hooks A, by passing 65 through the apertures C' and D' in the stationary grates C and D, are guided in their up-and-down motion in such a manner that they retain their relative positions to each other, having no sidewise or endwise motion what- 70 ever.

The hook A⁴ passes over the ridge C² on the 75 grate C in the downward movement of the hooks A, so as to prevent the latter from going farther down, whereby they assume the same position that they had before being raised.

In transferring the harness-threads F from one machine to the other, the upper ends of the same are simply unhooked from the collets by slipping their respective loops out between 80 the overlapping ends, or slipping the collets from the hooks, which latter is preferable.

The above mechanism is applicable to jacquards generally and to the machine shown in Patent No. 230,591, dated July 27, 1880. 85

Having thus fully described my invention, what I claim as new, and desire to secure by Letters Patent, is—

1. The combination, with the hooks A, of the detachable collets E, formed of spring-wires overlapped at their ends to receive between them the bends of the hooks, substantially as set forth.

2. The combination, with the hooks A and the threads F, having loops on their upper 95 ends, of the detachable collets E, formed of twisted spring-wires, having their ends overlapped intermediate the ends of the collets to form openings through which the bends of the hooks and the loops of the thread may be 100 passed, substantially as shown and described.

JAMES JACKSON.
